COMBINED SALT AND PEPPER SHAKER

Alexander Szopo, 346 Sudan St.,
New Brunswick, N.J. 08901

Filed Sept. 15, 1970, Ser. No. 25,015

Term of patent 14 years

Int. Cl. D7—01

U.S. Cl. D44—22

FIG. 1

FIG. 3

FIG. 2

FIG. 5

FIG. 4

FIG. 1 is a side elevational view of a combined salt and pepper shaker showing my new design;

FIG. 2 is a top plan view;

FIG. 3 is a bottom plan view;

FIG. 4 is an end elevational view;

FIG. 5 is an elevational view of the end opposite to the one shown in FIG. 4.

I claim:

The ornamental design for a combined salt and pepper shaker, as shown.
